W. C. DILLON, C. J. TOAY, W. H. TOAY, AND A. HANEY,
CASH DRAWER BURGLAR ALARM.
APPLICATION FILED JAN. 3, 1921.

1,406,447.

Patented Feb. 14, 1922.

UNITED STATES PATENT OFFICE.

WILLIAM C. DILLON, OF FORT DODGE, IOWA, CURTISS J. TOAY, OF AVALON, PENNSYLVANIA, WILLIAM H. TOAY, OF DES MOINES, AND ARCHIE HANEY, OF FORT DODGE, IOWA; SAID DILLON ASSIGNOR OF HIS ENTIRE RIGHT TO ALEXANDER B. RODERICK, OF DES MOINES, IOWA.

CASH-DRAWER BURGLAR ALARM.

1,406,447.

Specification of Letters Patent. Patented Feb. 14, 1922.

Application filed January 3, 1921. Serial No. 434,574.

To all whom it may concern:

Be it known that we, WILLIAM G. DILLON, CURTISS J. TOAY, WILLIAM H. TOAY, and ARCHIE HANEY, citizens of the United States, 5 residing at Fort Dodge, in the county of Webster, State of Iowa, Avalon, in the county of Allegheny, State of Pennsylvania, Des Moines, in the county of Polk, State of Iowa, and Fort Dodge, in the county of 10 Webster, State of Iowa, respectively, have invented a certain new and useful Cash-Drawer Burglar Alarm, of which the following is a specification.

The object of our invention is to provide 15 a cash drawer provided with a burglar alarm so adapted that when the currency within the drawer is removed therefrom an alarm will be given, parts being of simple, durable and inexpensive construction.

20 More particularly our invention relates to such a device that may readily and easily be installed upon the counter or cash drawers of a bank, and so adapted that when a certain portion of the money is removed from 25 the cash drawer an alarm will be rendered at some distant point, notifying the people that hear the alarm that the money has been removed from the cash drawer.

Still another object is to provide a device, 30 for containing currency that has a portion of the currency permanently therein for rendering an alarm device inoperative, while the remainder of the money or currency may be removed therefrom as would be the 35 case in the ordinary banking business. The device being so installed that anyone not familiar therewith, and who had no authority to remove the money out of the drawer would, by the removal of the money give 40 the alarm.

With these and other objects in view, our invention consists in the construction, arrangement and combination of the various parts of our device, whereby the objects 45 templated are attained, as hereinafter more fully set forth, pointed out in our claims and illustrated in the accompanying drawings, in which:

Figure 1 is a central, sectional view, taken through our device as installed on a bank 50 counter.

Figure 2 is a side elevation of our device, parts being broken away to better illustrate the construction.

Figure 3 is a top, plan view of the device 55 showing the arm for holding the device inoperative.

Figure 4 is a horizontal, sectional view, taken on the line 4-4 of Figure 1; and

Figure 5 is a modified form, showing the 60 arm for holding the device inoperative.

In the accompanying drawings we have used the reference numeral 10 to indicate generally a bank counter or cashier's drawer, which is provided with the partition members 11 which are of the ordinary construction and which are used for separating the 65 various denominations of currency.

It will be understood that our device is installed in each till or section so that removal of all of the currency of any one denomination will cause the alarm to ring.

The counter 10 is provided with an opening 12 and an annular recess in its upper surface 13. Our device which consists of a 75 tubular shaped member or casing 14 is provided with a flange 15 on its upper edge, which is received in the recess 13, while the tubular member or casing 14 extends through the opening 12 and projects down 80 below the under surface of the counter 10.

The flange 15 is provided with openings 16 for permitting screws 17 to be used for fastening the member 14 in position and against movement.

The lower end of the member 14 is screw threaded as at 18 for receiving the cap or closure member 19. The cap or closure member 19 is provided with a central opening 20 through which is extended the washer 90 21 which is of insulated material so that a contact member 22 may extend through the washer and be insulated from the remainder of the device.

The contact member 22 is provided with 95 a screw threaded portion 23 upon which are

received the nuts 24 and 25. The nut 24 may be tightened for holding the contact member against movement.

A wire 26 is received between the nuts 5 24 and 25. A weight member 27 is slidably mounted within the tubular shaped member or casing 14, and is provided with a pair of guide devices or bolts 28 and 29.

The guide devices 28 and 29 extend 10 through a slot 30 in the tubular shaped member or casing 14. The weight 27 is capable of vertical movement within the casing 14 and the movement thereof is limited by the slot 30.

15 The guide or bolt 29 is provided with a nut 31 so that a wire 32 may be received between the head of the guide or bolt and the nut 31. A bell 33 is connected to the wire 32. The wire 26 is connected to a 20 source of energy 34 and then to the bell 33 for completing the wiring system.

When the lower surface of the weight member rests upon the contact point 22 then a complete electrical circuit will be had and 25 the bell will be operated.

It will be understood that it is our intention to only have the bell operate at certain times, that is when the bank is being robbed and the currency being removed from the 30 cash drawer by someone without authority to do so.

In order to hold the weight member out of engagement with the contact point 22 and for breaking the circuit we have provided 35 an arm 35 which is received in a groove formed in the side of the weight 27 and is held fixed thereto by means of the guide devices 28 and 29.

The upper end of the arm 35 is formed at 40 right angles to the portion of the device which rests against the weight 27 so as to form a currency engaging member 36 which is slightly spaced above the upper edge of the weight 27 and substantially parallel 45 therewith.

Currency 37 is placed in the drawers or sections 11 with a portion of the currency resting below the lower edge of the member 36 and above the upper edge of the weight 50 27 as illustrated in Figure 1 of the drawings.

It will be seen that the placing of the currency in this position will prevent the weight member from moving downwardly and thus causing it to be held in such position that the electrical circuit will not be completed. The remainder of the currency will be placed in the ordinary way above the engaging member 36, and can be removed as in the case of the ordinary banking business.

60 It will be seen that if someone not familiar with the alarm would attempt to rob the bank and pull all of the currency out of the drawers or sections the weight 27 will then drop upon the contact 22 and turn in, the 65 alarm by ringing the bell 33.

It will also be understood that the bell 33 may be located in some convenient place so that the person robbing the bank will not know that he has turned in the alarm and that he has trapped himself.

An ordinary switch may be used for closing the circuit when it is desired to repair or remove all the currency from the sections as will be the case when the currency is placed in the vault.

The engaging member 36 is provided with an opening 37 so that an especially designed tool may be used for raising the weight member after it has once dropped.

In Figure 5 of the drawings we have 80 shown the engaging member 36 circular and of substantially the same outline as the opening within the casing 14.

It will be seen that our device may readily and easily be installed and is made of comparatively few parts, which when once installed will very seldom become out of order.

When the device is installed, the cap 19 is removed so as to permit the casing to be slipped through the opening 12. The weight 27 is then placed into the casing and the guide devices installed in position. The placing of the cap in the lower end of the casing or tubular member 14 completes the installation of our device.

It will be seen that we have provided a very effective cash drawer burglar alarm which is very simple in construction and arrangement.

Some changes may be made in the construction and arrangement of the various parts of our improved device without departing from the essential features and purposes of our invention, and it is our intention to cover by our claims, any modified 100 forms of structure or use of mechanical equivalents, which may be reasonably included within their scope.

We claim as our invention:

1. In a device of the class described an 110 alarm for money containers comprising a casing having a slot in its side, a cap fixed to the lower edge of said casing having an insulated contact point thereon, a weight of conductive material slidably mounted in said casing, guide devices fixed to said weight and extended through said slot, an arm fixed to said weight and provided with a portion spaced from the upper edge of the weight for receiving currency therebetween for 120 holding said weight up and whereby the removal of the currency will permit said weight to drop upon said insulated contact point for closing a circuit.

2. In a device of the class described a casing having a flange at its upper end and having its lower end screw threaded, a cap on said screw threaded end, an electrical contact member fixed on said cap and insulated therefrom, a second contact member slidably 130

mounted in said casing, including a weight member having an arm fixed thereto, an engaging member formed on the upper end of said arm, a guide device for preventing rotation of said weight within the casing, said guide device extending through the casing whereby an electrical wire may be fastened thereto, the parts being so arranged that currency may be placed below said engaging member for holding said second member out

of engagement with said first contact member and when the currency is removed the contact members will become engaged for completing an electrical circuit.

Des Moines, Iowa, October 30, 1920.
